UNITED STATES PATENT OFFICE

EDWIN J. DOWNING, OF DENVER, COLORADO, ASSIGNOR TO GARDNER-DENVER COMPANY, OF DENVER, COLORADO, A CORPORATION OF DELAWARE

TOOL RETAINER

Application filed December 31, 1928. Serial No. 329,644.

The object of the present invention is to provide a tool retainer in which the tool-engaging member or yoke is more securely held against any tendency to open under the strain of blows delivered to it by the tool that is retained thereby, the means that yieldingly resists the movement of the yoke moreover having merely a rectilinear movement as distinguished from a swinging or lateral movement.

10 In the accompanying drawings there is disclosed the preferred embodiment of the invention and therein—

Figure 1 is a plan view of the chuck end of a rock drill with the retainer in place.

15 Figure 2 is a longitudinal sectional view on the line 2—2 of Figure 1.

Figure 3 is a front elevation.

20 Figure 4 is a perspective view of the chuck housing.

Figure 5 is a perspective view of the retaining yoke.

Figure 6 is a sectional view on the line 6—6 of Figure 1.

25 The drill structure, it will be understood, may be of any desired type and includes a chuck end 7 with a chuck 8 therein to receive the shank 9 of a drill steel or other tool. This shank has the usual enlargement shown in the form of a collar 10. The tool, it will be understood, can be inserted and removed from the chuck 8, and when the drill is in operation it has a limited movement in the chuck.

30 Fitted on to the said chuck end is a housing 11 provided with the usual outstanding ears 12 to receive the side bolts of the drill. This housing is further provided on one side with an enlargement which includes a pair of spaced longitudinally disposed ears 13 and a central elongated portion 14 located between the ears 13 and provided with a longitudinal slot 15. This slot opens into a longitudinal chamber 16 that opens through the front end 40 of the enlargement.

35 A blow-resisting stirrup of substantially U-shape is mounted on the housing. It consists of side arms or bars 17 slidable in the ears 13 and having annular stop flanges 18 45 that limit their rearward movement. On the

50 rear end portions of the side arms are relatively heavy coiled springs 19 that bear against the rear ends of the ears and against nuts 20 located on and suitably locked to the rear terminals of the side arms. The front ends of said side arms are connected by a cross bar 21 preferably integral with the side arms. It will be noted by reference to Figures 2 and 3 that the cross bar 21 is located at one side of the shank 9 of the tool and is sufficiently spaced therefrom to at all times permit the passage of the collar past the same, so that in itself this stirrup does not interfere with the introduction and removal of the tool from the chuck.

55 The retaining member is in the form of a yoke 22 carried by a rearwardly extending arm 23 that swings in the slot 15 and has at its rear end an integral cross pin 24 constituting a pivot that is located in the chamber 16. The yoke 22 is adapted to embrace the shank of the tool as shown in Figure 3, but the space within it is insufficient to permit the passage of the collar 10. Consequently when in the position shown in Figures 2 and 3 this yoke, while permitting a limited movement of the steel, is in the path of the collar and therefore prevents the detachment of the steel from the chuck. The upper portion of the yoke is in the form of a relatively heavy body 25, and said body and yoke proper slide transversely of and against the rear side of the cross bar 21 of the stirrup. The front face of said yoke and body are provided with recessed seats 26 and 27, in which the cross bar 21 is adapted to engage when the yoke is in its operative and when it is in its inoperative position. The bearing of the yoke against the cross bar is secured by means of a coiled spring 28 located in the rear end of the chamber 16 and bearing against a washer 29 that in turn has a recess 30. Its front side constitutes a pivotal bearing for the cross pin 24 of the arm 23 of the yoke. The spring 28, it will be noted is very much lighter than the springs 19 of the stirrup. The arm 23 preferably has an outstanding finger piece 31 by means of which the yoke can be readily swung.

60 With this construction, it will be noted

that the yoke 22 can be swung transversely of the chuck and tool shank and to and from a position in the path of the collar 10 of said shank. When moved to either position the 5 cross bar 21 of the stirrup engages in one of the seats 26-27 and thus holds the yoke in its active or inactive position. By forcing the yoke transversely the cross bar 21 can be unseated as the spring 28 will yield and permit the rearward movement of the yoke. The 10 stirrups 17-21, however, has no lateral movement and consequently when the yoke is in its active position, as shown in Figures 2 and 3, any blow or strain imparted against it 15 due to the collar 10 striking it will be resisted by the stirrup and the springs 19. There is no tendency of the yoke to swing outwardly or to an inoperative position on account of such blow because the cross bar 20 21 of the stirrup constitutes a fulcrum against which the stirrup bears.

From the foregoing, it is thought that the construction, operation and many advantages of the herein described invention will 25 be apparent to those skilled in the art without further description, and it will be understood that various changes in the size, shape, proportion and minor details of construction may be resorted to without departing from 30 the spirit or sacrificing any of the advantages of the invention.

What I claim, is:

1. The combination with a chuck for holding a tool having an enlargement, of a tool 35 retainer comprising a yielding stirrup member mounted on the chuck, and a device having an independent mounting in the chuck and movably engaged with the stirrup member therewith, and movable to and from a position in the path of the enlargement of a tool placed in the chuck.

2. The combination with a chuck for holding a tool having an enlargement, of a tool 45 retainer comprising a yielding stirrup member mounted on the chuck, and a device pivoted on the chuck and on an axis transversely thereof, and having a portion movable to and from a position between the member and the enlargement of a tool placed in the 50 chuck in the path of the enlargement.

3. The combination with a chuck for holding a tool having an enlargement, of a stirrup having spaced portions slidably longitudinally of the chuck, spring means resisting such movement, and a retaining yoke having a mounting on the chuck between the spaced portions of the stirrups and having a part movable transversely of the stirrup in engagement therewith and to and from a position in the path of a tool placed in the chuck. 55

4. The combination with a chuck for holding a tool having an enlargement, of a stirrup, having spaced portions slidably longitudinally of the chuck and having a cross 65 bar in advance thereof, spring means resist-

ing such movement, and a retaining yoke pivoted on the chuck between the spaced portions and having a part movable transversely of the stirrup in engagement with the cross bar and to and from a position in the path 70 of a tool placed in the chuck.

5. The combination with a chuck for holding a tool having an enlargement, said chuck having longitudinal guideways, of a stirrup comprising side rods slidable in the 75 guideways and a cross bar connecting the side bars and located at the side and out of the path of the enlargement of a tool placed in and removable from the chuck, and a tool 80 embracing yoke mounted on the chuck between the guideway and slidably engaged with the cross bar of the stirrup and movable with respect thereto into and out of the path of the enlargement of a tool placed in the chuck. 85

6. The combination with a chuck for holding a tool having an enlargement, said chuck having longitudinal guideways, of a stirrup comprising side rods slidable in the 90 guideways and a cross bar connecting the side bars and located at the side and out of the path of the enlargement of a tool placed in and removable from the chuck, and a tool embracing yoke slidably engaged with the cross bar 95 of the stirrup and movable with respect thereto into and out of the path of the enlargement of a tool placed in the chuck, said yoke having recessed seats in which said cross bar detachably engages to hold the yoke.

7. The combination with a chuck for holding a tool having an enlargement, of a stirrup 100 slidably longitudinally of the chuck, spring means resisting such movement, and a tool-retaining yoke mounted on the chuck and movable to and from a position in the path of the 105 enlargement of a tool in the chuck, and having a portion movable behind and engaged by the stirrup.

8. The combination with a chuck for holding a tool having an enlargement, said chuck having longitudinal guideways, of a stirrup comprising side rods slidable in the 110 guideways and a cross bar connecting the side bars and located at the side and out of the path of the enlargement of a tool placed in and removable from the chuck, and a tool-retaining yoke mounted on the chuck and movable to and from a position in the path of the 115 enlargement of a tool in the chuck and having a portion movable behind and engaged by the cross bar.

9. The combination with a chuck for holding a tool having an enlargement, said chuck having longitudinal guideways, of a stirrup comprising side rods slidable in the 120 guideways and a cross bar connecting the side bars and located at the side and out of the path of the enlargement of a tool placed in and removable from the chuck, and a tool-embracing yoke having an arm pivoted on the chuck, 125 130

said yoke being slidably engaged with and being located behind the cross bar and movable to and from a position in the path of the enlargement of a tool in the chuck.

- 5 10. The combination with a chuck for holding a tool having an enlargement, said chuck having longitudinal guideways, of a stirrup comprising side rods slidable in the guideways and a cross bar connecting the side bars
 10 and located at the side and out of the path of the enlargement of a tool placed in and removable from the chuck, a tool-embracing yoke having an arm pivotally and slidably mounted on the chuck, said yoke being slidably engaged with and being located behind the cross bar and movable to and from a position in the path of the enlargement of a tool in the chuck, and a spring acting against the yoke to urge it forwardly.
 15 20. 11. The combination with a tool holding chuck including a housing having longitudinal ears and a longitudinal slot between said ears, of a stirrup comprising side arms slidable in the ears and a cross bar connecting the front ends of the side arms, springs on the rear ends of the side arms and resisting the forward movement of the stirrup, a tool-embracing retaining yoke having a rearwardly extending arm slidably and pivotally
 25 mounted in the slot, said yoke having its front face slidable transversely of and against the rear side of the stirrup's cross bar, and a spring bearing against the rear end of the yoke's arm to yieldingly urge the yoke against
 30 the cross bar.
 35 12. The combination with a tool holding chuck including a housing having longitudinal ears and a longitudinal slot between said ears, of a stirrup comprising side arms slidably in the ears and a cross bar connecting the front ends of the side arms, springs on the rear ends of the side arms and resisting the forward movement of the stirrup, a tool-embracing retaining yoke having a rearwardly
 40 extending arm slidably and pivotally mounted in the slot, said yoke having its front face slidable transversely of and against the rear side of the stirrup's cross bar, a spring bearing against the rear end of the
 45 yoke's arm to yieldingly urge the yoke against the cross bar, said spring being weaker than the springs on the side arms of the stirrup, and seats in the front side of the yoke for receiving the cross bar to hold the yoke
 50 against its movement with respect to said cross bar.
 55

In testimony whereof, I affix my signature.
 EDWIN J. DOWNING.
